W. T. KJELLAND.
BURGLAR ALARM.
APPLICATION FILED AUG. 1, 1917.

1,257,881.

Patented Feb. 26, 1918.

ATTORNEY

UNITED STATES PATENT OFFICE.

WILLIAM T. KJELLAND, OF EAST STANWOOD, WASHINGTON.

BURGLAR-ALARM.

1,257,881.

Specification of Letters Patent. Patented Feb. 26, 1918.

Application filed August 1, 1917. Serial No. 183,952.

To all whom it may concern:

Be it known that I, WILLIAM T. KJELLAND, a citizen of the United States, residing at East Stanwood, in the county of Snohomish and State of Washington, have invented new and useful Improvements in Burglar-Alarms, of which the following is a specification.

This invention is an improved burglar alarm, the object of the invention being to provide a cheap and simple alarm apparatus which is adapted to be attached to a door knob and which is set in operation by even a slight turning of the knob so that it is impossible for a person to even turn the knob of a door provided with the burglar alarm without setting the alarm in operation.

Another object of the invention is to provide an improved mechanism of this kind which is foldable and can be readily carried.

The invention consists in the construction, combination and arrangement of devices hereinafter described and claimed.

In the accompanying drawings:—

Figure 1 is an elevation, partly in section of a burglar alarm constructed and arranged in accordance with my invention, and with a door knob spindle and a key of the lock indicated in dotted lines.

Fig. 2 is a vertical sectional view of the same on the plane indicated by the line 2—2 of Fig. 1.

Fig. 3 is a horizontal sectional view of the same on the plane indicated by the line 3—3 of Fig. 1.

Fig. 4 is a detailed vertical sectional view, showing the alarm mechanism and its connections.

Fig. 5 is a similar view showing the link and its connections.

In the embodiment of my invention I provide an attaching member 1 which has a notch 2 in one side adapted to receive the sleeve A of a door knob and provided at the lower side of the notch with a shoe 3 to bear against the under side of the sleeve and provided at the upper side of the notch with a set screw 4 to bear on the spindle so that said attaching member may be readily detachably secured to the sleeve and caused to turn therewith when the knob is turned by a person attempting to enter through the door. The attaching member is here shown as hollow, and as made of sheet metal and

comprising side walls and top and bottom walls. A clamping member 5 is arranged at one side of the attaching member, is pivotally mounted between the side walls of the attaching member as at 6, and is provided at its lower end with a spring finger piece 7.

An arm 8 is pivotally attached at its upper end as at 9 to the lower portion of the attaching member and depends therefrom. Said arm has a slot 10 through which the key B of the door lock extends, the key serving to hold the arm against turning movement and to insure relative angular or pivotal movement between the arm and the attaching member when the latter is turned by the knob.

An alarm mechanism 11 is mounted on the lower portion of the arm and may be of any suitable construction. As here shown the alarm mechanism comprises a bracket or casing 12 secured on the arm 8. The winding shaft 13 is mounted in bearings in said bracket or casing and said arm and has the usual ratchet wheel 14 and the usual loose spur gear 15. The spur gear is provided with a spring pressed pawl 16 which engages the ratchet wheel. A spring 17 is attached at one end to and is coiled on the winding shaft and has its free end attached to a stud 18 which projects from the arm. A link 19 has a slot 20 through which said stud and the winding shaft extend so that the link is mounted for sliding movement. The spur gear engages a pinion 21 on a shaft 22. Said shaft has an escapement wheel 23. A shaft 24 is provided with an escapement 25 which coacts with the escapement wheel and is also provided with an arm 26 having a hammer 27 to strike a bell 28, said shaft being further provided with a vibrating arm 29. A spring trip 30 which normally engages behind a vibrating arm and holds the escapement in position to lock the escapement wheel is attached at one end to the bracket or casing 24 and at the opposite end to a trip member 31, said trip member being pivotally mounted on the winding shaft. The link 19 has a stop 32 on one side to engage one end of the trip member, and has a stop 33 on the opposite side to engage under the trip member, near the opposite end of the latter. Hence said trip member is caused to release the spring trip or detent element from the vibrating arm when

100

110

the link 19 is moved either upwardly or downwardly, and thereby start the alarm apparatus in operation. Said link is connected by a rod 35 to the attaching member, 5 said rod having a hook 36 at its upper end to engage in an opening in the bottom of the attaching member. The clamping member 5, when in normal position engages its spring 7 on the upper side of the hook to 10 lock the rod against longitudinal movement with respect to the attaching member.

In the event that the knob should be turned in either direction the attaching member turns therewith so that the rod 35 15 is caused to draw the link 19 in one direction or the other and hence either the stop 32 or the stop 33 of said link moves the free end of the trip member 31, thereby causing the detent spring to disengage the vibrating 20 arm and setting the alarm apparatus in operation. Hence an alarm is sounded in the event of even an attempt to open the door and at the first turning movement of the knob of the door lock.

25 By first disengaging the clamping member 5 from the hook of the rod 35 the latter may be unhooked from the attaching member 1 and the latter folded inwardly over the arm 8, thus compactly arranging the 30 burglar alarm and enabling the latter to be placed in a pocket or other receptacle.

While I have herein shown and described a preferred form of my invention I would have it understood that changes may be 35 made in the form, proportion and construction of the several parts, without departing

from the spirit of my invention and within the scope of the appended claims.

Having thus described my invention, I 40 claim:—

1. In an alarm mechanism of the class described, a winding shaft, a stud, a vibrating arm, a trip member pivotally mounted on the winding shaft and arranged to engage the vibrating arm, and a link having a longitudinal slot through which the winding shaft and stud extend, so that said link is 45 slidably mounted, said link having stop devices on opposite sides to engage said trip member so that the trip member will be 50 turned and caused to release the vibrating arm when the link is moved in either direction.

2. A burglar alarm of the class described comprising a relatively fixed member, an attaching member having means whereby the same may be secured to a door knob to be turned thereby, an alarm apparatus mounted on one of said members and tripping means for said alarm apparatus, to set the 60 same in operation, and including a connecting member extending to the other member so that relative angular movement of the attaching member and relatively fixed member will cause the alarm apparatus to be set 65 in operation, said attaching member and relatively fixed member being pivotally connected together and foldable one upon the other.

In testimony whereof I affix my signature. 70

WILLIAM T. KJELLAND.
